INTERNAL COMBUSTION ENGINE

Original Filed Nov. 13, 1924

Inventor
JOHN F. CRAWFORD,

James A. Walsh

Attorney

Patented Jan. 3, 1928.

UNITED STATES PATENT OFFICE.

JOHN F. CRAWFORD, OF RACINE, WISCONSIN, ASSIGNOR TO J. I. CASE THRESHING MACHINE COMPANY, OF RACINE, WISCONSIN, A CORPORATION.

INTERNAL-COMBUSTION ENGINE.

Original application filed November 13, 1924, Serial No. 749,795. Divided and this application filed October 28, 1926. Serial No. 144,763.

My invention relates to internal combustion engines, and particularly to the governor and pump thereof, which I associate and operate together in a simple and efficient manner as will more fully appear, and which improvement is a part of that which is the subject of my co-pending application, Serial No. 749,795, filed November 13, 1924, and of which this application is a division.

10 In the accompanying drawing, forming part hereof, Figure 1 is a longitudinal sectional view of that part of an internal combustion engine to which my improvement is applicable; Fig. 2 a detail section taken on the dotted line 2—2 in Fig. 1, and Fig. 3 is a detail section on the dotted line 3—3 in Fig. 1.

In said drawing 5 indicates the crank-case of any desired character, and 6 a fragment of the cylinder-block. The governor is enclosed in a housing, 7, and is of the centrifugal type. A governor-shaft, 8, is mounted in suitable bearings 9, 10, at opposite ends of the housing 7 and extends forwardly therethrough as shown in Fig. 1. Upon said shaft I mount a gear, 12, which is in mesh with and rotated by a cam-shaft gear, 12', or other driving element of the engine in a well known manner. Said gear 12 is 20 provided with grooves, 13, in which balls, 14, are fitted, and held in position by cone-bearing, 15, the latter being pressed against the balls by the pressure of a spring, 16, positioned in any desired manner, and acting, through pressure of a governor-arm, as 25 17, against a thrust bearing, 18, associated with said cone-bearing, the resultant operation being that the balls 14, actuated by centrifugal force, caused by rotation of gear 12, move out in grooves 13, thus overcoming 30 the spring tension applied to thrust-bearing 18, and close the usual throttle (not shown) which communicates with the governor arm 17. The governor-shaft 8, as indicated, extends forwardly of the engine structure for 35 connection with a pump comprising a housing, 20, cover 21, and a rotary impeller 22, said cover having a gland, 23, a water-tight connection for the governor-shaft 8 being provided by a packing, 24.

It will thus be seen that I provide a combined governor and pump, the latter requiring no bearings, as the bearings 9, 10, in housing 7 at all times maintain shaft 8 in

proper position for rotating the impeller 22. 55

In the water passage from the radiator, as 26, usually employed, through pump 20 and to the cylinders, indicated at 27, Fig. 1, several joints requiring packing material are necessary, which packing I install in a manner not to affect the height of the unit under which packing is placed. For example, if conventional packing was placed between the pump body 20 and crank-case 5, the pump would be raised the thickness of the packing, and upon renewal of packing, if not of proper thickness, the pump height would be changed, which would be detrimental to assemblage and operation. Therefore, I counterbore a recess, preferably 70 in crank-case 5, or such recess may be formed in any other unit to be attached to the case, and insert therein a ring, 28, or other element of suitable material and somewhat larger in depth than the counterbore, so that when the pump or other unit is clamped upon the crank-case a water-tight joint is provided, and at the same time the metal to metal dimensions of the connected elements 75 are thus maintained. 80

I claim as my invention:

1. In an internal combustion engine, a housing, a governor shaft mounted therein, a gear-wheel on said shaft for rotating the latter, actuating means carried by the gear-wheel, means for controlling contact of said actuating means with the gear-wheel, a pump casing on said engine, an impeller in said casing mounted on said shaft, and means on said engine for driving said gear-wheel to rotate said shaft and impeller. 85

2. In an internal combustion engine, a housing, a shaft mounted therein and extending outwardly therefrom, a gear-wheel embodying grooves mounted on said shaft, balls in said grooves, a bearing on said shaft engaging said balls, yielding means for controlling the contact of said bearing in relation to said balls, a pump on the outer end of said shaft, and means engaging said gear-wheel to rotate said shaft and pump. 90 95

3. In an internal combustion engine, a governor housing, a shaft mounted therein, a gear-wheel on said shaft, a bearing on said shaft, balls between said gear-wheel and said bearing, a thrust-bearing on said shaft engaging said bearing, yielding means contacting said thrust bearing to control the 100 105

movement of said bearing in relation to said balls, a pump on said shaft, and means engaging said gear-wheel for rotating the same and said shaft and pump.

- 5 4. In an internal combustion engine, a governor housing, a shaft mounted therein and extending therefrom, governor mechanism embodying actuating means, a governor member, means contacting with the actuating means for controlling the governor member mounted on said shaft, a pump-casing at the end of said shaft embodying a water passage, a cover for said casing into which said shaft extends, and a gland on
- 10 said shaft removably connected to said cover

for maintaining packing material about said shaft between said cover and gland.

5. In an internal combustion engine, a housing having bearings, a shaft supported by the bearings, a gear-wheel on the shaft 20 within said housing, actuating means adapted to engage the gear-wheel, a governor arm, means contacting with the actuating means for controlling the movement of the governor arm, a pump on the outer end of 25 the shaft, and means engaging said gear-wheel for actuating said shaft and pump.

In testimony whereof I affix my signature.

JOHN F. CRAWFORD.
